UNITED STATES PATENT OFFICE.

LOUIS A. SHERMAN, OF DETROIT, MICHIGAN.

TOOL FOR TRUING ABRADING-WHEELS.

SPECIFICATION forming part of Letters Patent No. 745,120, dated November 24, 1903.

Application filed July 5, 1902. Serial No. 114,372. (No model.)

To all whom it may concern:

Be it known that I, LOUIS A. SHERMAN, a citizen of the United States, residing at Detroit, county of Wayne, State of Michigan, have invented a certain new and useful Improvement in Tools for Truing Abrading-Wheels; and I declare the following to be a full, clear, and exact description of the invention, such as will enable others skilled in the art to which it pertains to make and use the same, reference being had to the accompanying drawings, which form a part of this specification.

This invention relates to tools for truing and dressing grinding or abrading wheels; and it has for its object a simple, practical, and efficient tool made from pressed and hardened disks of steel arranged to do the desired work.

20 The tool in which this invention is embodied retains its cutting properties or properties of dressing the hard material of the abrading-wheel for a long period of time until it is worn to the hub. It is made from disks of steel that are radially corrugated, and the periphery of the corrugated disk is notched at irregular intervals. Several disks of corrugated steel having different schemes of corrugation are placed side by side on a spindle or a bushing that runs on a spindle, and the spindle is held in a handle by which the tool is manipulated.

In the drawings, Figure 1 is a section longitudinal of the handle and longitudinal of the spindle. Fig. 2 is a side elevation of an abrading-disk. Fig. 3 is a section longitudinal of the handle, showing a side elevation of a corrugated disk. Fig. 4 is an edge view of a corrugated disk. Fig. 5 is a perspective view of a small portion of a disk. Fig. 6 is an end view of the tool, showing the different schemes of corrugation of the two disks.

1 indicates a forked handle in which there is a spindle 2. On the spindle 2 is mounted a bushing 3, that is arranged to rotate on the spindle. At one end of the bushing 3 is a collar 4, which serves as an abutment against which to hold the disk, hereinafter mentioned. On the bushing are several, at least

three, corrugated disks 5 6 7. These disks 50 are originally flat plates of uniform thickness, circular, and provided with a circular central aperture 8. The flat disks are corrugated with radial corrugations that vanish in the flat surface of the plate a short distance from the line which bounds the opening 8 and are bent to produce a waved outline on the periphery. The periphery is notched with notches 10, that are irregularly spaced around the entire periphery. The 60 disks are made with different schemes of corrugations—as, for example, in Fig. 2 there are shown fourteen corrugations and in Fig. 3 twelve corrugations—and in assembling the disks on the bushing they are assembled in a 65 way so that they will not nest—as, for example, the disk of Fig. 2 and the disk of Fig. 3 would be placed contiguous, the disk of Fig. 2 being placed between two disks of the Fig. 3 scheme, so that when the collar 4^a is 70 placed on the bushing and brought to a position to force the disks together they bear with the raised portions of the corrugations in contact and are prevented from nesting closely together, but are nevertheless held 75 quite firmly, and the bushing is allowed to turn on its spindle.

Provision is made for admitting oil between the bushing and the spindle through oil-holes 2^a. The handle is provided with a rest 1^a. 80

In operation the abrading-stone which is to be dressed is set in motion, and the notched and corrugated edges of the disk are held against that portion of the stone which is to be dressed. A rapid rotation is given to the 85 disks as soon as they come in contact with the moving stone, and short irregular blows are struck on the stone by the teeth of the tool, dressing it rapidly and easily.

What I claim is—

1. In a tool for dressing abrading-wheels, in combination with a handle, a spindle carried thereby, a bushing mounted on said spindle, a plurality of radially-corrugated metal disks arranged with different schemes of corrugation, whereby they are prevented from nesting mounted and rotated on said bushing, substantially as described. 95

2. In a tool for dressing abrading-wheels, the combination of a spindle, disks threaded upon said spindle contiguous to each other, said disks being stamped out of sheet metal
5 with different schemes of corrugation whereby they are prevented from nesting, substantially as described.

In testimony whereof I sign this specification in the presence of two witnesses.

LOUIS A. SHERMAN.
